Primary Examiner — Eric L Goodman*Assistant Examiner* — Lilyana Bekic*(74) Attorney, Agent, or Firm* — Collard & Roe, P.C.(57) **CLAIM**

The ornamental design for an inhaler, as shown and described.

DESCRIPTION

FIG. 1 is a left side view of an inhaler, showing my new design;

FIG. 2 is a rear view thereof;

FIG. 3 is a right side view thereof;

FIG. 4 is a front view thereof;

FIG. 5 is a top view thereof;

FIG. 6 is a bottom view thereof;

FIG. 7 is a top, left side and rear perspective view thereof; and,

FIG. 8 is a partial cross-sectional view taken in the direction of line 8-8 of FIG. 1.

The broken lines in the drawings depict portions of the inhaler that form no part of the claimed design.
